UNITED STATES PATENT OFFICE.

HENRY FARMER, OF RICHMOND, INDIANA.

PLANTER AND SEEDING-MACHINE.

SPECIFICATION forming part of Letters Patent No. 246,106, dated August 23, 1881.

Application filed July 16, 1879.

To all whom it may concern:

Be it known that I, HENRY FARMER, of Richmond, in the county of Wayne and State of Indiana, have invented a new and useful Improvement in Planters and Seeding-Machines, 5 of which the following is a specification.

My invention relates to improvements in corn-planters, having reference particularly to that part of the apparatus which prepares the 10 ground for the reception of the seed and covers the seed when dropped.

My invention consists, essentially, in the combination, with a shoe and opener, of furrow-covering shares having their forward straight 15 portions pivoted to studs upon the shoe and capable of vertical adjustment in connection with slotted studs thereon, while their rear portions are inclined downward in the direction of their length and curved inward toward 20 each other, all of which will be more fully hereinafter described in detail.

My invention also embraces other features of construction, which will be first described in detail, and specifically pointed out in the 25 claims.

My invention is embodied in mechanism illustrated in the accompanying drawings, in which—

Figure 1 is a longitudinal vertical section 30 taken through the seed-tube, shoe, and furrow-opener. Fig. 2 is a plan view of the shoe and attachments apart from the carriage-frame. Fig. 3 is a vertical cross-section of the shoe, taken through the bifurcation of the furrow-opener in rear of the seed-tube. Figs. 4 and 5 are similar cross-sections of slightly-modified 35 forms of the shoe, and Fig. 6 is a plan view of the furrow-opener detached from the shoe.

Similar letters of reference in the specification and drawings indicate similar parts.

The description of my improvements will be more readily understood in connection with the drawings, in which—

A designates the shoe; B, an opening at the 45 rear of the shoe corresponding with the opening through the bifurcated portion of the furrow-opener; C, the seed-dropping spout; D, the runner or furrow-opener, and E E the covering-shares.

In ordinary corn-planters the shoe is generally 50 a mere appendage to the furrow-opener

to regulate the depth of penetration; but in my improvements I make the furrow-opener a fixed appendage to the shoe. The shoe I construct preferably of cast-iron or steel, in a 55 form approximating the prow or forward portion of a boat, presenting the convex side to the earth and curving upward in front, to which point the width also diminishes, and at the sides from front to rear. This form, as will be 60 readily seen, not only economizes the draft-power in dragging the shoe through the newly-plowed ground, but also pulverizes the more friable clods of earth, and forces aside hard clods, stones, and other obstructions, leaving 65 a clear path of pulverized earth behind it in a shallow furrow, in the center of which is the deeper furrow formed by the runner and furrow-opener D. The condition in which the 70 shoe thus formed leaves the ground for the reception of the seed is most favorable for thoroughly covering the corn with well-pulverized earth by the covering-shares following after. This form also permits a thin and light construction without sacrificing necessary strength. 75

The runner and furrow-opener D is a blade disposed edgewise centrally upon the bottom of the shoe, turned up in front, and riveted or bolted to the shoe at that point. At the rear the runner is bifurcated to form a spreader, 80 which opens beneath a corresponding recess or opening, B, at the rear of the shoe. The sides of the bifurcated portion are extended a little higher than the runner, so that in attaching the runner D to the shoe these extensions pass up within the recess B, and are turned over the bottom of the shoe laterally, thus securing the runner at that point. The construction is shown in the cross-sectional views, Figs. 3 and 4. Besides forming a very 85 economical construction—the parts being separately made and easily fitted together and held by a single bolt—it enables either the runner or the shoe to be renewed independently when worn out. The shoe and runner may, however, 90 be cast together as one, as shown in the cross-section, Fig. 5, if preferred.

The shoe A is made sufficiently long and wide to sustain a frame carrying the seeding devices and the operator, when drawn over 95 plowed ground, the weight of which is designed to cause the shoe to sink the furrow-opener to 100

its full depth, and turn aside such obstructions as cannot be crushed and pulverized by the action of the shoe without changing the relative depth of the planting-furrow. The frame 5 is supported above the shoe by the seed-tube C, which is for this purpose provided above and below with lateral flanges or ears for attachment to the frame and shoe, and is thus constituted a supporting-standard, the forward 10 connection being made by a brace or bar in any convenient manner.

The covering-shares E E are blades extending rearward of the shoe and adjustably connected therewith in the following manner: At 15 each side of the shoe, at or near the rear, are two vertical lugs, F F, the forward ones being perforated by circular bolt-holes, and the rear ones having vertical slots formed therein. The shares E are pivoted at their forward ends to 20 the forward set of lugs, and by means of bolts passing through the slots of the rear lugs and the shares the latter are rendered adjustable vertically. The outside surfaces of the rear lugs, F, are roughened or serrated, and washers 25 with a similarly-serrated surface are interposed between the lugs and the nuts upon the adjusting-bolts of the shares, and the shares thus firmly held in the adjusted positions.

The lugs F may be cast with the shoe as part 30 of it, or may be formed separately and secured by rivets or bolts, and instead of the vertical slot in the rear lugs, a series of holes disposed vertically may be formed therein, and a removable pin or bolt used to secure the covering-share, and the washer dispensed with. 35

The rear ends of the covering-shares are curved over toward the center a sufficient distance to accumulate soil to properly cover the seed. The adjustability of the covering-shares upon the shoe renders it possible to cover the 40 seed to any desired depth, according to the character of the soil or desire of the user.

Having described my invention, I claim and desire to secure by Letters Patent—

1. In a corn-planter, the combination, with 45 the shoe A and opener B, of the furrow-covering shares E, having their forward straight portions pivoted to studs upon the shoe, and capable of vertical adjustment in connection with slotted studs F thereon, while their rear 50 portions are inclined downward in the direction of their length and curved inward toward each other, substantially as and for the purpose set forth.

2. The combination, with the shoe A and 55 opener B, of the furrow-coverers or shares E, having their straight portions pivoted to studs on the shoe, and their rear portions inclined downward in the direction of their length and curved inwardly toward each other, and the 60 slotted studs F, having serrated or roughened surfaces, and bolts and nuts, substantially as and for the purpose set forth.

HENRY FARMER.
